UNITED STATES PATENT OFFICE

2,200,386

APPARATUS FOR OPERATING UPON THE
HEEL PORTIONS OF SHOESFrank A. Eich, Melrose, Mass., assignor to United
Shoe Machinery Corporation, Borough of
Flemington, N. J., a corporation of New Jersey

Application November 18, 1938, Serial No. 241,211

12 Claims. (Cl. 12—42)

This invention relates to an apparatus by which may be performed operations upon the heel portions of shoes, such apparatus being particularly adapted for carrying out the method disclosed and claimed in the application for Letters Patent of the United States filed in my name on August 4, 1938, and bearing the Serial Number 223,055. In accordance with such method, double-pointed fastenings are driven into the heel-seat of a shoe, 5 with points projecting therefrom, after which a heel is forced upon these projecting fastenings to effect its attachment.

An object of my invention is to produce securely and conveniently either or both of the 15 above or similar operations. To this end, a frame carries a support arranged to present the heel-seat of a shoe for operations upon it, said frame also providing an attaching seat adapted to mount alternatively a mechanism for inserting 20 nails or other fastenings in the heel-seat and a mechanism for pressing a heel upon the inserted fastenings. The inserting mechanism may comprise a mold provided with passages and drivers movable in the passages, so the heel-seat may be 25 formed simultaneously with the insertion of the fastenings. The heel-pressing mechanism may have a heel-engaging member, such member and the drivers of the inserting mechanism being movable by a reciprocatory actuating member 30 movable upon the frame and common to both. The inserting mechanism and the pressing mechanism are preferably mounted in ways in the frame. There is means for securing the inserting mechanism upon the frame in an unvarying position, and the heel-pressing mechanism in different 35 positions, the latter being in accordance with different forms of heels. The mold of the inserting mechanism, whether it be used with or without the heel-pressing mechanism, and the shoe-support are movable relatively to cause the mold 40 to engage and form the heel-seat, and the drivers, which move in the mold-passages, have openings to receive the fastenings to be inserted. This permits the drivers to hold the double-pointed 45 fastenings for their insertion, there being retaining means for said fastenings, shown herein as springs carried by the drivers. To facilitate locating the work correctly during initial engagement with the mold, said mold is yieldable. This 50 may be by virtue of rods connected to the mold and movable in its support or carrier and springs which allow the rods to yield. In the illustrative apparatus, the mold is separably connected to the rods and has a retaining latch movable upon one 55 of these.

One of the several possible embodiments of the invention is shown in the accompanying drawings, in which:

Fig. 1 is a broken front elevation of my improved apparatus, with the fastening-inserting 5 mechanism in use;

Fig. 2, a central, vertical section through the operating elements, taken in a plane from front to rear of the apparatus;

Figs. 3 and 4 are partial sections in a like plane, 10 illustrating successive steps in the operation of the inserting mechanism;

Fig. 5 is a broken detail in perspective of the fastening-receiving end of one of the drivers, and

Fig. 6, a partial section in the plane of Fig. 2, 15 with the heel-pressing mechanism in use.

At 10 appears a frame having a forwardly extending arm 12, above which is an overhanging arm 14. Through a vertical bore in the arm 12 extends a spindle 16, splined to move longitudinally of the bore without rotation. It may be raised or lowered by a screw 18 having threaded engagement with it and stepped in the arm 12 upon a bearing 20. Below the arm, a hand-wheel 22 is secured to the screw to effect its rotation. 25 The spindle 16 at its upper extremity carries a shoe-support P, in the present instance in the form of a bed-piece 24, capable of adjustment upon the spindle and having an upwardly projecting pin 26 adapted to enter an opening in a last, as appears at L, and thus present a shoe S for the operations upon it. With this work-support may cooperate either of two interchangeable mechanisms A (Figs. 1, 2, 3 and 4) and B (Fig. 5), which are respectively adapted to insert fastenings in the heel-seat of the supported shoe and to force upon such fastenings a heel H. 35

The frame-arm 14 has depending from its forward end a portion 28 in which are formed opposite horizontal ways 30, 30. These ways receive and provide an attaching seat for the complementally shaped portion of a support or carrier for the inserting mechanism A, this carrier being shown as a block 32. The block is releasably latched in a definite position in its ways by 45 a spring-actuated plunger 34 movable horizontally through the arm-portion 28 and entering a depression in the block. Extending vertically through the block are six passages. Four of these, designated by the numeral 36, are located 50 near the block-corners, while the others, 38, 38, are respectively near the front and rear of the center-line. In the passages 38 rods 40, 40 are movable, being held against withdrawal downwardly by the heads of screws 42, threaded into 55

their upper extremities and contacting with shoulders formed in the passages 38. At the bottom, each rod 40 has a head 44 received within a T-slot 46 extending from the rear close to the front of a pressure member 48, which is thus removably supported. To prevent accidental displacement of this member, one of the rods 40 has longitudinal bores of different diameters, the lower being smaller and containing a headed 10 latching pin 50. The end of the pin projects through the bottom of the rod, entering a depression in the member 48 to retain said member upon the supporting rods. A spring 52 interposed between the head of the pin and the corresponding screw 42 threaded into the upper portion of the latch-passage, allows the latch to yield and release the member when the operator draws it forward. In the under side of this member 48 is a mold-depression 54, which may 15 register with the heel-seat of a lasted shoe carried upon the pin 26 of the support P. When the work-supporting spindle 16 is raised by the rotation of the screw 18, the heel-seat will be forced against the mold to be formed thereby 20 to correspond to the cup of a heel which is to be attached. In this action, the mold 48 first yields vertically against the resistance of plungers 56, of which there are four carried in the bores 36 (Fig. 1). The plungers are forced normally down 25 against the upper surface of the mold by springs 58 contained in bores within them, these springs abutting at their upper extremities against shoulders in the block-bores 36. Near their tops, the plungers are shouldered to engage rings 60 set 30 in recesses about the lower portion of the bores and held in place by screws 62. In the mold are vertical passages 64 through which fastening-drivers may operate, these passages being arranged in accordance with a particular inserting 35 design. The manner in which the mold is mounted allows it to be changed readily for others having their driver-passages corresponding to different designs. The mold, as it yields against the springs 58 when the spindle 16 is 40 raised, puts such preliminary pressure upon the heel-seat that the shoe may be adjusted readily upon its support to enable the operator to more exactly produce the desired registration between the work and the mold. Then, as the elevation 45 of the spindle continues, the upper surface of the mold contacts with the opposed lower surface of the block 32 to cause the yield to be arrested, with the consequent application of final molding pressure.

50 Movable in passages 65 in the block and in the registering mold-passages 64 are fastening-drivers 66 held in a plate 67. This plate is received in ways 68, 68 at opposite sides of a head 70 at the bottom of an actuating spindle 72, guided to 55 move vertically in a bore in the frame-arm 14. An axial bore through the spindle 72 is threaded to receive a screw 74 rotatable by a hand-wheel 77 in bearings 76 upon the arm. In the lower end of each driver is a bore 78 (Fig. 5) adapted to 60 receive the longer shank *a* of a nail N of the collar type, the flange or collar *b* of which rests against the end of the driver outside the bore. This leaves projecting from the driver an opposite shank *c* of the nail, which is shown as bifurcated. After the shank *a* has been inserted in the driver-bore, it is yieldably retained therein, as by a leaf-spring 80 secured in a recess at the side of the driver by a screw 82. An angular end 65 of the spring projects through an opening in the driver-wall for engagement with the nail.

When the opposite surfaces of the mold 48 and the block 32 are in contact after the elevation of the shoe by its support, the points of the nail-shanks *c* are in proximity to the lower openings in the mold-passages 64. Then, when the driver-plate 67 is lowered as a result of the rotation of the hand-wheel 77 and screw 74, the descent of the drivers 66 forces the shanks through the heel-seat, so their divided portions are separated and clinched upon the plate *l* of the last L. The extent to which the drivers should be lowered to bring their ends to or just beyond the openings in the driver-passages into the mold-depression 55 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

The mechanism B, by which the heel H is pressed upon the shanks *a* of the inserted nails, is illustrated in Fig. 6 of the drawings. The ways 30 of the frame-arm-portion 28, when the block 32 of the inserting mechanism A has been removed, receives the complementally shaped portion of a carrier-block 100 of mechanism B. 25 This has adjustable upon it as to angle by a worm and worm-segment connection 102, the upper section 104 of a heel-tread-abutment 106, the latter being adjustable transversely of the work-support P by its mounting in ways 108 in the section 104. A screw 109 retains this adjustment. The block 100 is secured in the ways 30 by a screw 110 (Fig. 1), which will hold said block, with the abutment 106, in different positions longitudinally of the shoe S upon the support. Into the ways 68 in the reciprocatory head 70 is inserted, in place of the driver-plate 67, a plate 112 provided with a rear depending portion 114 which passes down through a space in the block 100. A cover-plate 116 attached to the block holds the plate-portion 114 for vertical movement. At the lower extremity of the portion 114 is pivoted upon an eccentric pin 118 a holder 120 for a rear heel-abutment in the form of a fork 122 arranged to engage the peripheral wall of the heel H. By an adjustment at 124, the space between the arms of the fork may be adjusted, while their angle longitudinally of the shoe may be varied about the pin 118. This pin, by its eccentric arrangement, may be turned to release or lock toothed engagement between the holder 120 and an opposed contact member 126 upon the portion 114. By moving the block 120 in its ways and securing it by the screw 110 and by raising or lowering the fork 122 by turning the hand-wheel 77, the position of the heel-abutment members 106 and 122 may be altered for most effective engagement with heels of different pitches. The vertical position of the adjusted fork 122 may be maintained by rotating a screw 128 (Fig. 2) threaded into the frame 10, until its head bears against the lower edge of the hand-wheel. The engagement of the heel-abutments may be controlled further by the devices at 102, 109, 118 and 124. With these adjustments correctly made for the form of the heel to be attached, the operator applies openings *h*, which have been drilled in the heel to correspond to the inserting design, to the shanks *a* of the nails N in the heel-seat of the supported shoe and 75

raises said shoe and heel by rotating the hand-wheel 22 to elevate the support P. This forces the shoe-parts together to effect the attachment.

In using the apparatus, the block 32 of the inserting assembly A, with the fastening-drivers 66 in the passages 65, will be placed in the frame-ways 30 and the driver-plate 67 in the spindle-ways 68 and fixed in a definite position by the locking plunger 34. The block-passages and contained drivers will be in accordance with the inserting design which is to be employed. To the rods 40 is applied a mold 48, which will impart the desired contour to the heel-seat of a shoe S being operated upon, the mold being releasably retained by the latch-pin 50. The shanks a of nails N will be inserted in the openings 18 of the drivers, with the protruding divided shanks c preferably arranged in predetermined angular positions about their axes to give the best relation to the periphery of the heel-seat of the shoe (Fig. 1). They are thus retained by the driver-springs 80. The lasted shoe is placed upon the pin 26 of the support P (Fig. 2), and the spindle 16 raised by turning the hand-wheel 22, until the heel-seat contacts with and forces up the mold against its springs 58. While under this preliminary pressure, the shoe may be adjusted by its movement with the last-bed-piece 24, until the heel-seat registers properly with the molding depression 54. Then, continued rotation of the hand-wheel brings the upper surface of the mold and the lower surface of the block 32 together to stop the elevation of the mold and cause the application of final forming pressure to the heel-seat (Fig. 3). The shanks c of the nails are now in the mold-passages 64, and upon rotating the hand-wheel 77, the spindle 72 will lower the drivers 66 to force the divided nail-shanks through the heel-seat and upset them upon the last-plate 1 (Fig. 4). With the nails thus inserted, the operator turns the hand-wheel 77 reversely to withdraw the drivers and the hand-wheel 22 to lower the work-support. He may then free the inserting assembly A by releasing the plunger 34 and remove said assembly from the apparatus, substituting the pressure assembly B, with its block 100 in the stationary ways 38 and its plate 112 in the reciprocatory ways 68. Correct pressure-applying and -retaining engagement of the tread-abutment 106 and the rear abutment 122 with the heel H will have been assured by the adjustment of the block in its ways under the control of the screw 110 and the independent vertical movement of the fork-carrier 112, 114 by the screw 74, together with such customary adjustments at 102, 109, 118 and 124 as may be desirable. A heel H, drilled through its cup with openings h corresponding to the design of the inserting nails, is applied to said nails, and the support again raised by rotating the hand-wheel 22. The heel being held against upward movement by the contacting abutments, the nails will be forced into the heel-openings. This action will be continued until the periphery of the heel-cup is firmly seated upon the lasted-over upper-material, when the support may be lowered by its hand-wheel to permit the removal of the heeled shoe.

Having described my invention, what I claim as new and desire to secure by Letters Patent of the United States is:

1. In a machine for operating upon the heel portions of shoes, a frame, a shoe-support carried by the frame, and a reciprocatory member movable upon the frame toward and from the sup-

port, said frame having a portion located in operative relation to said reciprocatory member and providing an attaching seat, said attaching seat being adapted to mount alternatively a fastening-inserting mechanism including a heel-seat-mold provided with passages and fastening-drivers movable in the passages by said reciprocatory member, or a heel-engaging mechanism having a member movable by said reciprocatory member. 5

2. In a machine for operating upon the heel portions of shoes, a frame, a shoe-support carried by the frame, and a reciprocatory member movable upon the frame toward and from the support, said frame having a portion located in operative relation to said reciprocatory member and providing an attaching seat, said attaching seat having ways adapted to receive and mount alternatively complementally shaped portions of a fastening-inserting mechanism including a heel-seat-mold provided with passages and fastening-drivers movable in the passages by said reciprocatory member, or complementally shaped portions of a heel-engaging mechanism having a member movable by said reciprocatory member. 10 15 20

3. In a machine for operating upon the heel portions of shoes, a frame, a shoe-support carried by the frame, and a reciprocatory member movable upon the frame toward and from the support, said reciprocatory member having connecting means thereon, said frame having a portion located in operative relation to said reciprocatory member and providing an attaching seat, said attaching seat being adapted to mount alternatively a fastening-inserting mechanism including a heel-seat-mold provided with passages and fastening-drivers movable in the passages by and detachably connected to said connecting means on said reciprocatory member, or a heel-engaging mechanism having a member detachably connected to said connecting means on 30 35 40 said reciprocatory member and movable thereby.

4. In a machine for operating upon the heel portions of shoes, a shoe-support, a mold provided with passages, the support and mold being relatively movable to cause said mold to engage and form the heel-seat of a shoe upon the support, and drivers movable in the passages and having openings to receive the fastenings to be inserted. 45

5. In a machine for operating upon the heel portions of shoes, a shoe-support, a mold provided with passages, the support and mold being relatively movable to cause said mold to engage and form the heel-seat of a shoe upon the support, drivers movable in the passages and having openings to receive the fastenings to be inserted, and springs carried by the drivers and contacting with the fastenings in the openings. 50 55

6. In a machine for operating upon the heel portions of shoes, a shoe-support, a mold provided with passages, the support and mold being relatively movable to cause said mold to engage and form the heel-seat of a shoe upon the support, means arranged to permit the mold to yield during such engagement, and fastening-drivers movable in the passages. 60 65

7. In a machine for operating upon the heel portions of shoes, a mold-support, a mold yieldable thereon and provided with passages, a shoe-support, means arranged to move the supports 70 relatively to establish forming engagement between the mold and the heel-seat of a supported shoe, and fastening-drivers movable in the mold-passages.

8. In a machine for operating upon the heel 75

- portions of shoes, a mold-support, a mold provided with driver-passages, rods connected to the mold and movable in the support, springs permitting the rods to yield upon the support, a shoe-support, means arranged to move the shoe-support to establish engagement between the heel-seat of a supported shoe and the mold, and fastening-drivers movable in the mold-passages.
9. In a machine for operating upon the heel portions of shoes, a mold-support, a mold provided with driver-passages, rods connected to the mold and movable in the support, springs permitting the rods to yield upon the support, a shoe-support, means arranged to move the shoe-support to establish engagement between the heel-seat of a supported shoe and the mold, fastening-drivers movable in the mold-passages, and means for retaining the fastenings in engagement with the drivers.
10. In a machine for operating upon the heel portions of shoes, a frame, a shoe-support guided thereon, means arranged to raise and lower the support, a carrier mounted upon the frame and provided with passages, a heel-seat-engaging member mounted upon the carrier and having passages alined with the carrier-passages, an actuating member movable in the frame, and a driver-plate reciprocated by the actuating member.
11. In a machine for operating upon the heel portions of shoes, a frame, a shoe-support guided thereon, means arranged to raise and lower the support, a carrier mounted upon the frame and provided with passages, a heel-seat-mold guided to move upon the carrier with passages alined with the carrier-passages, springs interposed between the mold and the carrier, an actuating member movable in the frame, and a driver-plate reciprocated by the actuating member and having drivers movable in the passages of the carrier and in the heel-seat-mold.
12. In a machine for operating upon the heel portions of shoes, a frame, a shoe-support guided thereon, means arranged to raise and lower the support, a carrier mounted upon the frame and provided with passages, rods guided in the carrier, a heel-seat-mold separably mounted upon the rods, a latch for the mold movable upon one of the rods, an actuating member movable in the frame, and a driver-plate reciprocated by the actuating member and having drivers movable in the passages of the carrier and in the heel-seat-mold.

FRANK A. EICH.
